UNITED STATES PATENT OFFICE

DOROTHY LONG, OF NEW YORK, N. Y., ASSIGNOR TO FRANKLIN SIMON & COMPANY, INC.,
OF NEW YORK, N. Y., A CORPORATION OF NEW YORK

DESIGN FOR A DRESS

Application filed January 9, 1931. Serial No. 38,261. Term of patent 3½ years.

To all whom it may concern:

Be it known that I, DOROTHY LONG, a citizen of the United States and a resident of New York, in the county of New York and State of New York, have invented the new, original, and ornamental Design for a Dress, of which the following is a specification.

Reference is had to the accompanying drawing, forming part thereof, wherein

The figure is a front perspective view of a dress showing my new design, the rear being plain.

I claim:

The ornamental design for a dress substantially as shown and described.

DOROTHY LONG.
